NEEDLE VALVE

Chester B. McAulay, Palo Alto, Calif., assignor to
 Joshua Hendy Iron Works, a corporation of
 California

Application November 12, 1937, Serial No. 174,166

19 Claims. (Cl. 137—139)

This invention relates generally to pressure activated control valves and more particularly to a valve construction of the needle or plunger type which is adapted for positive pressure fluid control.

In this type of valve, trouble has been caused by the plunger or needle sticking, particularly in open position. As the needle approaches the closed position in many of the previous structures, it extends beyond and overhangs its supports and guides to such an extent that there is always present the tendency to jam or cock. Frequently the castings are finished only on one side and adequate ribbing is omitted to reduce the manufacturing expense, so that the needle gradually changes shape through warping and tends to stick. Unless the plunger or needle is properly supported at all times—in the closed, in the open, and in the intermediate positions—it may sag out of line and jam with consequent losses and expense to make it operative again. The problems though easily recognizable, have resisted solution in a practicable economical way.

Another problem in the successful operation of valves of this type is preventing the needle from slamming against its seat. Slamming is the sudden movement of the needle towards its seat near the end of its stroke. This wears out the valve seat and induces dangerous pressure rises in the pipe line upstream of the valve. Some of this difficulty is caused by the accumulation of air or gas in the operating chambers within the valve assembly. Part is due to pressure changes which are external of the valve assembly. As the needle approaches the closed position and the hydraulic pressure on the downstream face of the needle is reduced if there is no corresponding reduction of pressure on the inside face of the needle, there is a very marked tendency for the plunger to seat suddenly.

In the attempts to eliminate slamming the prior art shows valves with a multiplicity of tandem control chambers. This arrangement alone however will not accomplish the objects here solved and overcome the problems met in actual operation.

Another source of operating trouble is directly attributable to the accumulation of air or gases within these several operating chambers of the valve assembly. When the liquid used to supply pressure for actuating the valve, is run into the varicose chambers, there is a tendency for the air or gas contained therein to separate from the liquid and accumulate within the chambers. Gases being compressible will, if allowed to ac-

cumulate in sufficient quantity, make reliable control of the valve impossible and unmanageable and cause the needle to make sudden unpredictable movements as the hydraulic balance of pressure changes. Numerous specialized devices for releasing the accumulation of gases and air have been used before, each with its individual operating problems and all relying upon the operator remembering to check some special releasing means.

It is an object of the present invention to provide a construction with a plurality of operating chambers but which at the same time will provide for the automatic exhausting of air and gases in the chambers. It is therefore another object of the present invention to produce a valve construction which will prevent the sudden acceleration of the needle towards its seat. Still another object is to form a valve in which twisting, warping, cocking, and jamming of the needle are eliminated.

It is another object of the present invention to provide for the release of said gases, which naturally rise, through the liquid control ports without the addition of nozzles or any other sort of device or specialized equipment.

A further object is to provide a valve of the plunger or needle type which will respond positively and accurately to pressure fluid and which will follow closely any adjustment in the setting of the valve control element.

It is also an object and feature of the present invention to provide a balanced action and secure responsive, accurate control.

Still further objects are to provide a construction of maximum simplicity, economy and ease of assembly, and having such further advantages and capabilities as will later more fully appear, and which are inherently possessed thereby.

The invention further resides in the combination and construction, and arrangement of parts illustrated in the accompanying two sheets of drawings and while there is shown therein a preferred embodiment, it is to be understood that the same is capable of and susceptible to modification and change and comprehends other details and constructions without departing from the spirit of the invention or its scope.

Referring now to the drawings:

Fig. 1 is a view of a needle valve partly in elevation and partly in vertical section.

Fig. 2 is a detail of a fluid port.

Fig. 3 is a section taken on the line III—III of Fig. 1.

Fig. 4 is a view of the control ports taken on the line IV—IV in Fig. 1 and looking in the direction of the arrows.

Fig. 5 is an enlarged view in section of a guide support taken on the line V—V in Fig. 1.

Fig. 6 is an enlarged detail in plan view of the cover on the outlet ports.

Referring now more particularly to the drawings, the numeral 10 generally indicates the entire valve composed of an outer housing and an inner valve assembly. The outer cylindrical body housing is preferably made in two parts 11 and 12 for ease in assembly and so that internal operating members may be reached for repair or replacement without tearing down the entire valve. The rearward or upstream portion 11 of the valve housing narrows or decreases in diameter to that of the conduit or pipe line (not shown) conveying the liquid to the valve so that it may be secured thereto by means of the annular flange 13 provided on the valve housing. To this rearwardly extending portion of the valve housing 11, but on the interior thereof is attached a smaller concentric cylindrical member 14 by means of a plurality of radial webs or ribs 15 and 15a. With this inner cylindrical member 14 concentrically held and spaced within the outer housing, an annular fluid passage 16 is formed therebetween.

The forward portion of the valve housing 12 is joined to the rearward portion in any convenient manner and is progressively reduced in section, the diameter conforming in shape to and providing a seat for the needle 17 of the valve assembly. The downstream terminus of the housing member 12 is likewise provided with an annular flange 18 adapted for attachment to a discharge conduit or pipe line or to a discharge seat retaining ring 18a as is shown in Fig. 1. Attached to the forward valve housing 12 by means of a plurality of radial webs or ribs 20 is an inner annular, somewhat conical casing 21 which is joined flush at its external surface with the cylindrical member 14. Thus there is formed a continuation of the annular fluid passage 16 already described, by the forward outer housing member 12, the conical concentric casing 21 and the needle 17. The inner surface of annular casing 21 is reinforced to form an extended bearing surface 22 along which the cylindrical bearing surface 23 of the needle 17 travels in the movement of opening and closing for regulating the amount of flow through the valve. The downstream portions of the webs or ribs 20 are faced with bearing surfaces 24 (see Fig. 5), which are substantially continuations of the bearing surface 22 and keep the cylindrical portion 25 of the needle 17 and its bearing surface 23 in proper alignment, at all times, with requisite support as it travels from open to closed position and vice versa. In this manner the twisting or cocking of the needle 17 is entirely eliminated.

As in all valves of this type there are provided replaceable contact rings 26 and 27 at the seating where wear is likely to take place.

Attached in any suitable manner to the plunger 65 or needle 17 is an inner hollow cylindrical member 30 provided for a portion of its length with outer bearing sleeve 31. Attached to the upstream end of this hollow tubular member 30 is a closure member 32 provided with openings 33 and a disk-like piston head member 34. All of these being attached, move in unison in response to pressure exerted particularly on either side of the piston head 34. The outer perimeter of the piston head 34 is provided with a bearing surface 35 which travels along the bearing of the inner

surface 36 of the member 14. Toward the downstream portion of the hollow cylindrical member there is a port 37 providing free communication between chambers X and Z through the member 30 and via ports 33.

The conical head 14 of the upstream portion of the valve assembly is formed in two parts with a cap portion 40 which is joined flush on the outer surface with the conical portion 14. The cap portion 40 is provided with inwardly converging 10 struts or webs 41 to support the shaft 42 and the housing 43 for the pinion 44 and rack 45. The rack 45 is mounted on the closure portion 32 of the hollow cylindrical member 30 and is moved in a horizontal plane by the movement of the cylindrical member 30 thus bringing about a rotation of the shaft 42 directly and positive with respect to the position of the needle.

It will thus be seen that in the valve assembly there are three tandem chambers provided. One 20 is provided by the enclosure of the conical end cap portion 40, the piston head 34 and the closure member 32. This chamber will hereinafter be referred to as pressure chamber X. The only portions within this chamber which move in response to pressure are piston head 34, closure member 32 and rack 45, although, as will be explained subsequently, a like pressure is applied against the inner surfaces of 25a and 17 both of which move as a unit and in unison.

The second chamber is enclosed between the piston head 34, the bearing surface 36 of the cylindrical member 14, the stationary diaphragm 47, which is rigidly secured to member 21 and ultimately also to member 14, and bearing surface 35 31. This chamber will hereinafter be referred to as pressure chamber Y. The only portion moving in this chamber in response to pressure is the piston head 34.

A third chamber is enclosed between the stationary diaphragm 47 and the inner surface of the needle 17 and 25a. By means of the ports 33 and 37 and the hollow cylindrical member 30 the pressure chambers X and Z are in constant inter-communication and the pressure of the two 45 chambers is equalized at all times. Since the communication is such that fluid may readily pass between chambers X and Z the piston head 34, the closure 32, the tubular member 30 and the needle 17, including its portions 25 and 25a, 50 whenever the valve assembly is actuated in the normal operation of the valve, the pressure operates in both chambers at the same time.

The stationary diaphragm 47 has a reinforced concentric opening therein provided with a bearing surface 48 against which slides the bearing surface 31 of the hollow cylindrical member 30 in the normal operation of the valve.

Chamber X is connected at its top portion through the wall of the conical portion of member 14 by port 50 and through rib 15a and outer member 11 by means of passageway 54 and port 51 to the control means. This passage to the control means does not communicate with but passes through the annular fluid passage 16 and is non-65 communicating with respect to any other portion of the valve assembly except that chamber X is in communication with chamber Z. Chamber Y is in separate communication with the control means through the aperture 52 in the inner cylindrical member 14 and through the outer rearward housing by reason of passageway 55 through rib 15a and port 53. There are similar triangular escaping ports 52 which empty directly into the channel 16. This passageway 55 is noncommuni- 75

cating with respect to the flow of liquid through the annular passage 16 as well as any other portion of the valve assembly. The complete separation of passageways 54 and 55 permits the introduction of liquid into either chamber X or Y at the same time atmospheric pressure is being introduced into the other, or liquid flow may be maintained in both chambers X and Y at the same time. Thus pressure conditions are established within the valve assembly but it is obvious that the movable cylindrical member 30 and the piston 34 move as a unit with the needle in response to variation of the pressure conditions.

In operation, the control of liquid in the conduit or pipe line is effected by the movement and positioning of the needle of the valve assembly which is actuated by controlling pressures within the chambers X, Y, and Z. Where equal fluid pressure is maintained within the chambers X, Y, Z, there will be the tendency for the movable needle 17, the cylindrical member 30 and the piston 34 to travel to the right hand toward the seat 27 because of the piston 34 being in hydraulic balance and the needle 17 being out of hydraulic balance. However as long as the fluid cannot escape from chamber Y pressure will be increased in this chamber to establish a balanced condition so that needle 17 cannot travel. Further with fluid flowing through the annular passage 16 there will be some pressure within this passage exerted on the outer surface of the needle 17 to counteract the internal pressure.

When fluid pressure is maintained within chambers X and Z and reduced pressure is maintained within chamber Y the needle 17 will travel to the right, overcoming any pressure exerted in the annular passage 16, due to the area of the piston 34 being greater than the exposed external surface of the needle 17. Travel will continue to the right just as long as the pressure in chamber Y is less than that in chambers X and Z with allowance for the external pressure from the flow from passage 16.

When fluid pressure is maintained in chamber Y and reduced pressure is maintained in chambers X and Z and the movable needle 17, the cylindrical member 30 and piston head 34 will move to the left or away from the seat 27 into the open position.

With the forces available it is possible to secure a delicate adjustment and control to open, to close, or to hold the needle in any intermediate position by controlling the relative pressures in chambers X, Y, and Z.

In eliminating the slamming of the needle to the valve seat when nearing the closed position, there are provided a plurality of ports 52 which are substantially triangular in plan, which is best seen in Fig. 2, the apex pointing toward the needle seat. The ports 52 are so positioned that as the cylindrical bearing surface 35 of the piston 34 travels to closed position it will gradually close the ports 52 but owing to the triangular shape of the ports the area is rapidly diminished and effects a throttling of the pressure fluid discharged from chamber Y and so materially reduces the closing speed.

It should further be noted that chamber Z is not required to control the movement of the valve. However, it is not practicable to eliminate this chamber and therefore it becomes necessary to provide means to discharge the fluid when the needle 17 moves into open position. The discharge and entry provided is through chamber X, port 33, tubular member 30 and port 37, which is

the intercommunication between the two chambers and permits chamber Z to respond only in connection with and through chamber X.

To prevent the accumulation of air and gases in chamber Z a small hole 56 directed downstream at an angle passes entirely through the conical casing 21 venting the chamber. Ports 50 and 52 being at the top of the chambers X and Y respectively, release any air or gases which may be given off from the pressure fluid and will automatically vent through these ports and be discharged to the atmosphere through the apertures 51 and 53 and the control elements, which may be, for example, similar to those shown in Kinzie Patent 1,998,458. Any equivalent control means may, of course, be used.

It will be seen that the movement of the needle in the opening and closing operation at all times finds proper rear support and guidance by means of piston 34. This is also true with respect to the movable portion 25 bearing against the member 21. These two bearing points are located at a sufficient distance apart to accomplish the result and are also located a sufficient distance away from the axis to adequately guide the needle 25 movement despite the terrific weights and pressures encountered in the normal operation. All this is in addition to the rib guides 24.

Although the operation has been described and illustrated with respect to a needle valve of the type constructed for free discharge into the atmosphere of the liquid passing through, it should be understood that the principles of this invention may be used where the liquid passing through the valve discharges into a closed conduit or pipe line whether of the same diameter or smaller than that of the inlet conduit or pipe line. It is likewise to be understood that even though the description of the mechanism and operation herein indicates a flow through the valve from left to right in Fig. 1 that the flow through the valve may be in either direction.

I claim:

1. A pressure operated valve comprising a valve housing and a concentrically spaced valve assembly including a fixed capped cylindrical member, a movable needle adapted for sliding movement within said cylindrical member, guides extending the full length of the needle stroke, a piston substantially greater in diameter than said needle positioned at the end of said cylindrical member opposite to said needle and adapted for movement within said cylindrical member, a fixed diaphragm spaced intermediate the piston and the needle, an axial tubular member joining said piston and said needle whereby all move as a single unit, the capped cylindrical member and the movable piston defining one end chamber, the needle and the fixed diaphragm defining the other end chamber and said piston and said diaphragm defining a central chamber non-communicating with respect to said end chambers, ports in said tubular member through which said end chamber defined by said needle and fixed diaphragm may receive pressure for actuating the valve, the closing movement being obtained by admitting pressure fluid to the end chambers which communicate freely by means of said movable ported tubular member and decreasing the pressure in the non-communicating central chamber, and the opening movement being obtained in a vice versa manner.

2. A pressure operated valve comprising a valve housing and a concentrically spaced valve assembly including a fixed capped cylindrical member, a movable pointed needle adapted for sliding

movement within said cylindrical member, guides extending the full length of the needle stroke, a piston substantially greater in diameter than said needle positioned opposite the pointed end thereof and adapted for movement within said cylindrical member, a fixed diaphragm spaced intermediate the piston and the needle, an axial tubular member joining said piston and said needle whereby all move as a single unit, the capped end and the movable piston defining one end chamber, the needle and the fixed diaphragm defining the other end chamber and said piston and said diaphragm defining a central chamber, ports formed in said tubular member opening into each of said end chambers, continuous means for escapement of air or gas from each of said chambers, said chambers being adapted to receive pressure for actuating the valve, the closing movement being obtained by admitting pressure fluid to the end chambers which communicate freely by means of said movable ported tubular member and decreasing the pressure in the noncommunicating central chamber and the opening movement being obtained in a vice versa manner.

5. A pressure operated valve comprising a valve housing and a concentrically spaced valve assembly including a fixed capped cylindrical member, a movable pointed needle adapted for sliding movement within said cylindrical member, guides extending the full length of the needle stroke, a piston substantially greater in diameter than said needle positioned opposite the pointed end thereof and adapted for movement within said cylindrical member, a fixed diaphragm spaced intermediate the piston and the needle, an axial tubular member joining said piston and said needle whereby all move as a single unit, the capped end and the movable piston defining one end chamber, the needle and the fixed diaphragm defining the other end chamber, and said piston and said diaphragm defining a central chamber, continuous means for escapement of air or gas from each of said chambers but said means with respect to the central chamber, being triangular in shape with the apex pointed toward the needle seat and adapted to substantially reduce in area restricting escapement as the needle nears its seat, ports formed in said tubular member communicating with said end chambers, said chambers being adapted to receive pressure for actuating the valve, the closing movement being obtained by admitting pressure fluid to the end chambers which communicate freely by means of said movable ported tubular member and decreasing the pressure in the noncommunicating central chamber and the opening movement being obtained in a vice versa manner.

3. A pressure operated valve comprising a valve housing and a concentrically spaced valve assembly including a fixed capped cylindrical member, a movable pointed needle adapted for telescopic movement within said cylindrical member, guides extending the full length of the needle stroke, a piston substantially greater in diameter than said needle positioned opposite the pointed end thereof and adapted for movement within said cylindrical member, a fixed diaphragm spaced intermediate the piston and the needle, an axial tubular member joining said piston and said needle whereby all move as a single unit, the capped member and the movable piston defining one end chamber, the needle and the fixed diaphragm defining another end chamber, and said piston and said diaphragm defining a central chamber non-communicating with respect to said end chambers, ports communicating said end chambers formed in said tubular member, continuous means for escapement of air or gas from each of said chambers, said means associated with the central chamber adapted to be substantially reduced in area by said piston as it approaches closed position, the closing movement being obtained by admitting pressure fluid to the end chambers which communicate freely by means of said movable tubular member and decreasing the pressure in said central chamber, and the opening movement being obtained in a vice versa manner.

4. A pressure operated valve comprising a valve housing and a concentrically spaced valve assembly including a fixed capped cylindrical member, a movable pointed needle adapted for telescopic movement within said cylindrical member, guides extending the full length of the needle stroke, a piston substantially greater in diameter than said needle positioned opposite the pointed end thereof and adapted for movement within said cylindrical member, a fixed diaphragm spaced intermediate the piston and the needle, an axial tubular member joining said piston and said needle whereby all move as a single unit, the capped end and the movable piston defining one end chamber, the needle and the fixed diaphragm defining the other end chamber and said piston and said diaphragm defining a central chamber, continuous means for escapement of air or gas from each of said chambers, but said means with respect to the central chamber being triangular in shape and adapted to substantially reduce in area restricting escape-

ment as the needle nears its seat, ports formed through said tubular member into each of said end chambers, said chambers being adapted to receive pressure for actuating the valve, the closing movement being obtained by admitting pressure fluid to the end chambers which communicate freely by means of said movable ported tubular member and decreasing the pressure in the noncommunicating central chamber and the opening movement being obtained in a vice versa manner.

5. A pressure operated valve comprising a valve housing and a concentrically spaced valve assembly including a fixed capped cylindrical member, a movable pointed needle adapted for telescopic movement within said cylindrical member, guides extending the full length of the needle stroke, a piston substantially greater in diameter than said needle positioned opposite the pointed end thereof and adapted for movement within said cylindrical member, a fixed diaphragm spaced intermediate the piston and the needle, an axial tubular member joining said piston and said needle whereby all move as a single unit, the capped end and the movable piston defining one end chamber, the needle and the fixed diaphragm defining the other end chamber, and said piston and said diaphragm defining a central chamber, continuous means for escapement of air or gas from each of said chambers but said means with respect to the central chamber, being triangular in shape with the apex pointed toward the needle seat and adapted to substantially reduce in area restricting escapement as the needle nears its seat, ports formed in said tubular member communicating with said end chambers, said chambers being adapted to receive pressure for actuating the valve, the closing movement being obtained by admitting pressure fluid to the end chambers which communicate freely by means of said movable ported tubular member and decreasing the pressure in the noncommunicating central chamber and the opening movement being obtained in a vice versa manner.

6. A needle valve for controlling the flow of liquid through a housing, including an inner housing member surrounding a needle, a tubular body fixed centrally to said needle, a cylindrical wall fixed peripherally to said needle and slidably within said inner housing member, a piston fixed to said tubular body, a stationary diaphragm slidably surrounding said tubular body between said piston and said needle, a chamber end fixed to said housing and to said inner housing and arranged to form with said piston and said inner housing a chamber, ports disposed through said tubular body whereby said chamber and a chamber constituted by said tubular body, said needle, said cylindrical wall, said inner housing, and said stationary diaphragm may communicate freely, said stationary diaphragm, said inner housing, said tubular body, and said piston defining therebetween a chamber non-communicating with respect to the other chambers.

7. A needle valve substantially as described in claim 6, wherein said needle is of substantially smaller diameter than said piston.

8. A needle valve for controlling the flow of liquid therearound, said valve having three pressure chambers defined by a needle, a fixed diaphragm, a piston head of substantially greater diameter than said needle, and a stationary capped cylindrical member, wherein said fixed diaphragm and piston separate the center one of said chambers from the end ones of said cham-

bers; an apertured, movable tubular member providing free intercommunication between said end chambers, said center chamber being non-communicating with respect to said end chambers.

5 9. A needle valve for controlling the flow of liquid therearound having therein a central and two end pressure chambers formed by a needle, a fixed diaphragm, a piston head of substantially greater diameter than said needle, and a stationary capped cylindrical member, a tubular member slidably disposed through said fixed diaphragm and fixed to said piston head and said needle for movement as a unit, ports in said tubular member permitting communication there-through between said end chambers, and means 10 for maintaining said central chamber non-communicating with respect to said end chambers.

10 15. A pressure operated valve comprising a valve housing and a concentrically spaced valve assembly including a fixed capped cylindrical member, a movable needle adapted for sliding

movement within said cylindrical member, a piston positioned within the end of said cylindrical member opposite said needle and adapted for movement within said cylindrical member, a fixed diaphragm spaced intermediate the piston and 5 the needle, an axial tubular member joining said piston and said needle for unitary movement, said capped member and the movable piston defining an end chamber, the needle and the fixed diaphragm defining another end chamber and said 10 piston and said diaphragm defining a central chamber non-communicating with respect to said end chambers, ports through said tubular member communicating said end chambers, the closing movement being obtained by admitting pressure fluid to the end chambers which communicate freely by means of said movable ported tubular member and decreasing the pressure in said central chamber, and the opening movement being obtained in a vice versa manner. 15

CHESTER B. McAULAY. 20
